CHESTER A. FRICK, OF MUNCIE, INDIANA, ASSIGNOR TO GLASCOCK BROTHERS MANUFACTURING COMPANY, OF MUNCIE, INDIANA, A CORPORATION OF INDIANA.

GUIDE FOR BOTTLE REFRIGERATORS.

Application filed August 8, 1925. Serial No. 48,961.

My invention relates to improvements in bottle dispensing refrigerators and particularly to that type wherein there is provided U-shaped tubular channels through which the bottles are adapted to be passed, the bottle being inserted in the channel at one end and being forced through the channel and out the other end by the insertion of succeeding bottles.

10 In this type of refrigerator it is desirable that the bottles be inserted with their corresponding ends extending in the same direction and preferably inserted neck first. If one bottle is inserted bottom first and the 15 next succeeding bottle neck first the bottles are apt to jam and block the easy feeding of bottles through the channels or cause breakage.

One of the objects of my invention is to 20 provide means whereby the insertion of the bottles in correct position is insured.

For the purpose of disclosing my invention I have illustrated one embodiment thereof in the accompanying drawings in 25 which.

Fig. 1 is a plan view of a refrigerator embodying my invention;

Fig. 2 is a transverse sectional view thereof;

30 Fig. 3 is an enlarged sectional view of the intake end of one of the channels, and

Fig. 4 is an enlarged sectional view of the delivery end thereof.

In the structure illustrated I provide a 35 suitable support or frame 1 carrying an outer corrugated semi-cylindrical tub 2 and an inner tub 3 of substantially the same shape only slightly smaller and nesting within the outer tub. The corrugations of 40 the two tubs are so related as to form water communicating U-shaped tubular passageways 4, the delivery ends of the channels or passageways 4 are closed by suitable closures or covers 5 which are normally held closed 45 by a spring hinge 6. The tops of these covers 5 are plain and the covers lie in recesses 7 so that the covers are substantially flush with the top of the refrigerator. By this arrangement it is difficult to open the 50 cover from the exterior. The intake end of each of the tubular channels is provided with a plurality, preferably 2, spring pressed stops or plungers. Each of these

plungers comprises a sleeve 8 having at its outer end an annular flange 9 and operating within the sleeve is a plunger 10 the stem 11 of which is reduced and interposed between the bottom of the plunger 10 and an in-turned annular flange 12 at the bottom of the sleeve 8 is a coiled spring 13 which normally projects the plunger 10 into the tubular channel and in the path of the bottle. The sleeve 8 is counter-sunk in a suitable opening 14 in a part of the supporting frame 15. These spring pressed plungers are located a sufficient distance below the top of the refrigerator to prevent the insertion of the fingers and a bottle so that the plunger can not be manually pressed out of the path of the bottle. Normally these spring 70 plungers project into the path of the bottle and sufficiently far into the tubular channel to provide stops to prevent the insertion of a bottle bottom end first. However, if the bottle is inserted neck end first the portion 75 of the neck which is comparatively small in diameter will pass the plungers and the sides of the neck acting as cams will push the plungers back into their sockets permitting the bottle to readily pass into the tubular channel. Hinged covers 16 maintain the receiving ends of the channels closed when the bottles are not being inserted and these covers are provided with knobs 17 to enable the same to be readily raised or opened. Due to the fact that the covers 5 can not be 80 opened, or are difficult to be opened from the exterior of the refrigerator, the operator must insert the bottle in the receiving side, or end of the tubular channel, and due to the spring pressed plungers 10 he must insert the bottle neck first so that the bottles will always be fed into the refrigerator neck first and at the receiving end only. As the 85 bottles are pushed through the channels the delivered bottles will automatically open the closure 5 to permit the operator to grasp the bottle.

I claim as my invention:

1. A bottle refrigerator comprising a support, a pair of semi-cylindrical tubs 90 nestingly mounted on said support, the space between said tubs being formed into a series of circumferential channels each having two open ends, a closure for one end of each of 95 said channels normally operable from the 100 105

interior only and means for preventing the insertion of a bottle in the opposite end of the channel bottom end first while permitting said bottle to be inserted neck first.

5 2. A bottle refrigerator having substantially U-shaped bottle receiving tubular channels, means for closing one end of each of said channels normally openable from the interior only and means at the opposite end 10 of said channel for preventing the insertion of a bottle bottom first while permitting the insertion thereof neck first.

3. A bottle refrigerator having a U-shaped bottle receiving tubular channel, means for 15 closing one end of said channel normally openable from the interior only and a radially movable spring pressed plunger at the opposite end of said channel normally projecting into the path of the bottle and having 20 a stop preventing the bottle from being inserted in said channel bottom end first

and adapted to be retracted by the sides of the bottle when the same is inserted neck first.

4. A bottle refrigerator having a substantially U-shaped bottle-receiving tubular channel, through which the bottles are adapted to be passed axially, and means for insuring the insertion into said channel of a bottle neck first, comprising a plurality of 25 spring projected plungers extending transversely into the mouth of said channel to close said channel against the entry of a bottle butt first while being adapted to be pushed back by the cam action of the neck 30 of the bottle as the bottle is inserted neck first.

In witness whereof, I, CHESTER A. FRICK, have hereunto set my hand at Muncie, Indiana.

CHESTER A. FRICK.
